FRANK A. ROOME, OF ANTWERP, BELGIUM, ASSIGNOR TO WESTERN ELECTRIC COMPANY, INCORPORATED, OF NEW YORK, N. Y., A CORPORATION OF NEW YORK

TELEPHONE SYSTEM

Application filed August 23, 1929, Serial No. 387,846, and in Great Britain November 16, 1928.

This invention relates to switching trunk circuits for use at toll operators' positions for selectively extending incoming toll lines to automatic and manual exchanges.

8 An object of the invention is to increase the number of outgoing switching trunk groups, and the number of trunks in each group, that are directly accessible at a single toll operator's position and at the same time 10 effect economies in the amount of apparatus and space required for carrying out the necessary functions.

In attaining this object the switching trunk circuits terminate in finder switches 15 and the invention provides for continuous hunting by these switches at the will of the toll operator. The finder switches are of the homing type, this rendering it possible to apply the principle of grading to the finder 20 multiple and thus reduce the number of outgoing trunks to a minimum. The invention also permits the number of directions and the 25 number of trunks outgoing in each direction to be unrestricted and governed only by the traffic conditions, and moreover it permits the trunks of any or all of the groups to be distributed in any order. Consecutive or otherwise, around the finder banks.

According to one feature of the invention 30 each switching trunk circuit terminates in a finder switch having access to a plurality of groups of outgoing trunks and means is provided which, in response to an operation on the part of the toll operator, causes the finder 35 switch to hunt until it engages an idle trunk in a wanted group of outgoing trunks.

According to a further feature a preparation 40 switching circuit is provided over which a connection is adapted to be first made to an idle outgoing trunk extending to a wanted exchange the connection being subsequently transferred to a regular switching trunk circuit under the operator's control.

The accompanying drawings show four 45 embodiments of the invention but it will be understood by those versed in the art, that various other changes may be made without departing from the spirit of the invention.

Fig. 1 shows a jack-ended switching trunk 50 circuit provided with direction keys.

Fig. 1a shows a switching trunk extending to a distant exchange.

Fig. 2 shows a cordless switching trunk circuit and preparation circuit provided with direction keys.

Fig. 3 shows a jack-ended switching trunk circuit provided with a dial-operated common marking switch.

Fig. 4 shows a cordless switching trunk circuit and preparation circuit provided with a dial-operated marking switch.

Referring now to Fig. 1 this circuit shows a toll switching trunk circuit TST originating in an individual jack TJ at the toll board and terminating in the brushes *a*, *b*, *c* and *d* 65 of a trunk finder TF. Three relays *Jhr*, *Clr*, *Sbr* are associated with the trunk finder TF and three relays *Ptr*, *Shr*, *Ogr* are common to all the switching trunk circuits of a given toll operator's position.

The arc of the finder TF has 100 sets of terminals to each of which is connected a trunk outgoing to a manual or automatic exchange. The *a*, *b* and *c* terminals are multiplied throughout a group of finders at two or 75 more operator's positions but the *d* terminals are multiplied only over the finders belonging to a given operator's position. The toll operator has a strip of simple push button direction keys *DK₁*, *DK₂*, etc. By pressing one of 80 these direction keys, after a toll plug TP has been inserted in the jack TJ of a switching trunk, the finder TF of that switching trunk hunts and stops on the first free outgoing trunk OJ to the exchange indicated by the 85 direction key which has been pressed.

The circuit provides for continuous hunting so long as the direction key remains pressed.

The finder has a home position which makes 90 it possible to apply the principle of grading to the finder multiple and thus reduce the number of outgoing trunks to a minimum. So far as the operation of the circuit is concerned, the number of directions and the number of trunks outgoing in each direction are 95 unrestricted and determined only by the traffic conditions. Moreover the circuit does not demand that the trunks to a particular direction shall be spaced or grouped in any partic- 100

ular sequence. The only condition is that the *d* terminals of all the trunks in a given direction shall be strapped together. Signalling from the called exchange takes place over the *c* brush of the finder.

5 When the plug is withdrawn the whole circuit restores to normal.

Circuit operation

- 10 When the toll operator plugs into the switching trunk circuit jack TJ, the sensitive relay *Jhr* operates over both its windings in series with the cord circuit sleeve relay *Sr*. The resistance of the windings of relay *Jhr* is such that the relay *Sr* in the cord does not operate at this moment. At its left-hand front contact *Jhr* prepares a circuit for the power magnet *P* of the finder and at its right-hand contact prepares a circuit for 70 relay *Clr*.
- 15 The operator now presses one of the direction keys *DK₁*, *DK₂*, etc., according to the exchange to which the toll switching connection is to be extended. The left-hand contact 75 of key *DK* completes the circuit for the power magnet *P* which starts hunting, and the right-hand contact of the key connects the test relay *Ptr* to the *d* terminals of all trunks outgoing in the required direction. When the 80 brush carriage arrives at the terminals of a free trunk, the test relay *Ptr* energizes having found potential over the right-hand contact of key *DK*, brush *d* of the finder, outer right back contact of relay *Clr*, brush *c*, and 85 the sleeve relay *Tar* of the trunk circuit. At 90 its front contact relay *Ptr* closes a circuit for its low resistance left-hand winding in series with the slow operating relay *Shr* thereby making the *c* terminal busy. Relay *Shr* operating energizes relay *Cgr* which in turn energizes *Clr* via right-hand front contact of relay 95 *Jhr*. Relay *Clr* locks over its own front inner right-hand contact. Relay *Clr* permanently opens the circuit for the power magnet, 100 connects the tip and ring from the jack through to the outgoing trunk, disconnects the *d* brush and common test relay *Ptr* from the *c* brush, and connects the latter to the marginal relay *Slr*. The operation of *Clr* releases relays *Ptr*, *Shr* and *Cgr*.

105 The equipment connected to the *c* terminal of the outgoing trunk may vary according to the requirements of the circuits in the distant exchange.

110 In the case shown in Fig. 1a of the drawing, high resistance relay *Tar*, shunted by the lower resistance *R*, energizes in series with marginal relay *Slr* when the trunk is picked up by the finder *TF*. Marginal relay *Slr* also 115 operates which in turn operates relay *Sr* of the toll cord circuit to light the supervisory lamp *SL* which indicates to the toll operator that an outgoing trunk has been connected to whereupon she may release the key *DK*.

120 65 Operation of relay *Tar* completes a circuit

to operate relay 2 in the trunk circuit which can be traced from battery, right-hand winding of relay 2, inner normal contacts of relay 3, lower left-hand winding of repeating coil 4, lower right-hand winding of repeating coil 5, winding of polarized relay 1, contacts of relay *Tar*, upper right-hand winding of repeating coil 5, upper left-hand winding of repeating coil 4, outer normal contact of relay 3 and left-hand winding of relay 2 to ground. Operation of relay 2 lights the trunk lamp 6 over an obvious circuit which is extinguished when the plug 9 is inserted in the called subscriber's line.

125 The polarized relay 1 does not operate at this time due to the direction of the current flow in the previously traced circuit. When the called subscriber answers supervisory relay 8 in the trunk circuit operates which in turn operates relay 3 which reverses battery and ground with respect to the terminals of polarized relay 1, which relay thereupon operates to close an obvious energizing circuit of relay *Tbr* which relay in operating opens the low resistance shunt around the high resistance relay *Tar*, thereby increasing the resistance of the circuit including marginal relay *Slr* to a point where it releases, thereby 130 releasing relay *Sr* in the cord circuit and extinguishing the lamp *SL* as an indication that the called subscriber has answered.

135 When the called subscriber "hangs up" relay 8 releases which in turn releases relay 3 to again reverse the current flowing through polarized relay 1, which relay thereupon releases which releases relay *Tbr*. This again shunts relay *Tar* and lowers the resistance of the circuit including relay *Slr* which again operates to close the circuit of relay *Sr* and light the supervisory lamp *SL* in the toll cord 140 as an indication that the called subscriber has hung up.

145 The release of the switching trunk circuit TST is effected by withdrawing the plug *TP* from the jack *TJ* thus releasing all relays of the circuit. A circuit is then closed over the outer left-hand back contact of relay *Clr*, left-hand back contact of relay *Jhr* and the off-normal contact *INT* of the finder for the power magnet *P*, to cause the finder to rotate until 150 it reaches the home position which is marked by the opening of the off-normal contact *INT*.

155 Referring now to Fig. 2 this shows a cordless toll switching trunk circuit *TST* and preparation circuit *PC*. The preparation circuit is shown in the upper part of the drawing the toll operator's position being equipped with one preparation circuit only. The switching trunk circuit proper occupies the lower part of the drawing and each switching trunk is permanently associated with a particular toll line *TL* to which it may be connected by means of the holding key *JHK* so that the toll operator has as 160 many switching trunks as toll lines.

The function of the switching trunk circuit is to establish a connection from the toll line to a distant manual or automatic exchange.

The function of the preparation circuit is to prepare a connection to a manual or automatic exchange and later under the control of the toll operator to transfer this connection to the switching trunk and toll line for which it has been prepared, as soon as these latter have become free from their previous connection. In effecting this transfer, the preparation switch maintains the connection over the distant exchange and marks the terminal on which the preparation finder is standing in the position multiple. The switching trunk finder then hunts for the marked terminal and takes over the prepared connection after which the preparation circuit is restored to normal.

The switching trunk circuits and preparation circuit terminate in the brushes of trunk finders TF, PF having 100 sets of terminals to each of which is connected a trunk outgoing to a manual or automatic exchange. The *a*, *b* and *c*, terminals are multiplied throughout a group of finders, but the *d* and *e* terminals are multiplied only over the finders belonging to a given operator's position.

The switching trunk circuit contains two relays *Jhr* and *Clr* which control the circuit and there is also associated with it a signalling relay *Slr* which may be equipped in the toll position or at the switch rack.

The preparation circuit contains two relays *Phr* and *Ptr* and a signalling relay *Ppr*, whose functions are identical with those of relays *Jhr*, *Clr* and *Slr*. In addition it has two relays *Tpr* and *Dbr* and a transfer key *TK* which are concerned with the transfer of a connection from the preparation circuit to a toll switching trunk.

There are provided in addition three relays *Ptr*, *Shr* and *Cgr* which are common to the whole position.

The toll operator has a strip of simple push button direction keys *DK₁*, *DK₂*, etc. By pressing one of these direction keys after a holding key *JHK* or *PHK* has been thrown, the finder of the switching trunk engaged hunts and stops on the first free outgoing trunk to the distant exchange, indicated by the direction key which has been depressed. The circuit provides for continuous hunting so long as the direction key remains pressed.

The restoring of a key *PHK* or *JHK* returns the switching circuit to normal and in the case of *JHK* disconnects it from its toll line circuit.

Circuit operation

(1) *Toll switching trunk.*—Referring to Fig. 2, if it is desired to, at once, connect a toll line such as *TL* with a trunk such as *OJ*, the operator throws the locking junction

holding key *JHK* of the switching trunk and toll line, the ground at the outer contact of this key operates relay *Jhr* which prepares at its left-hand contact the circuit for the power magnet *PTF* of the switching trunk circuit finder *TF* and at its right-hand contact connects up the battery for relay *Clr*. The operator now presses one of the direction keys *DK₁*, *DK₂*, etc., according to the exchange to which the toll switching connection is to be extended. The left-hand contact of the key *DK* completes the circuit for the power magnet *PTF* which starts hunting. The right-hand contact connects the test relay *Ptr* to the *l* terminals of all trunks outgoing to the required direction. When the brush carriage arrives at the terminals of a free trunk *OJ* in this direction, the test relay *Ptr* energizes having found potential over the right-hand contact of key *DK*, brush *e* of the finder, back contact of relay *Dbr*, outer righthand back contact of relay *Clr*, brush *c* and the sleeve relay *Tar* of the trunk circuit. At its front contact relay *Ptr* closes a circuit for its lower resistance left-hand winding in series with the slow operating relay *Shr* and thereby marks the terminal busy. Relay *Shr* operating energizes relay *Cgr* which in turn energizes *Clr* which will remain locked over its own inner right-hand front contact. Relay *Clr* permanently opens the circuit of the power magnet *PTF*, connects line contacts from the holding key *JHK* to the *a* and *b* brushes of the finder *TF* disconnects the *d* and *e* brushes and the common test relay *Ptr* from the *c* brush and connects the latter to relay *Slr* which operates in series with the low resistance at the *c* terminal of the trunk. When *Slr* operates, it lights the signalling lamp *SL*. The operation of *Clr* releases relays *Ptr*, *Shr* and *Cgr*, while the lighting of the lamp *SL* indicates to the toll operator that the outgoing trunk has been connected, whereupon she may release the direction key *DK*.

The equipment at the *c* terminal of the outgoing trunk may vary according to the requirements in the distant exchange and for purposes of illustration will be understood to be the same as shown in Fig. 1a and described in connection with Fig. 1. Signalling is produced by the operation and releasing of relay *Tbr* under the control of the supervisory relay *S* at the distant exchange and is such that when relay *Tbr* operates, and at its back contact removes the shunt circuit to the high resistance winding of relay *Tar*, relay *Slr* releases and extinguishes the signalling lamp *SL*.

The release of the circuit is made by restoring the holding key *JHK* which releases relay *Jhr* and thereby permits relay *Clr* to release. The power magnet *PTF* then finds a circuit closed over the back contacts of *Clr* and *Jhr* and the off-normal contact *INT*

of the finder so that the finder rotates until it reaches the home position which is marked by the opening of the off-normal contact INT.

5 To set up a connection on the preparation circuit the operator depresses key PHK and a direction key DK. The preparation circuit operates to select an idle trunk in the desired direction in exactly the same manner as the toll switching trunk circuit the operation of which has been fully described, with the exception that the connection from the *e* brush of the finder PF to the *e* brush does not pass over a contact of relay Dbr. When 15 an idle trunk is engaged the supervisory relay Ppr energizes and lights the signalling lamp PL.

(2) *Transfer of a connection from the preparation circuit to a toll switching trunk circuit.*—As soon as the operator is ready to extend the calling toll line TL to the prepared trunk OJ she throws the key JHK of that switching trunk thereby energizing relay Jhr, but does not again use the direction 20 keys. Instead, the operator throws the transfer key TK which need not be a locking key as the transfer will take a maximum of 2 seconds to complete. The transfer key operates relays Tpr and Dbr. Relay Dbr 25 disconnects the *e* brush of all free switching trunk finders so that the finder which hunts for the preparation switch will not test the *e* terminal of any free trunks. Relay Tpr over its inner front contact connects the common test relay Ptr to the *e* brush of the preparation finder. At its left-hand front contact Tpr completes the circuit for the power magnet PTF of the toll switching trunk finder TF which had been prepared by the 30 operation of relay Jhr. At its right outer contact Tpr connects test potential to the *d* terminal of the line on the position multiple. The switching trunk finder rotating finds this potential on its *d* brush when arriving 35 at the marked terminal and passes this potential on to the narrow testing *e* brush which causes the finder to test and center in the regular way, the circuit to the test relay being closed over the *e* wire of the position 40 multiple and the stationary *e* brush of the preparation circuit and thence to relay Ptr which operates. The operation of Ptr results in the opening of the driving circuit 45 and the operation and locking of relay Clr 50 of the toll switching trunk in the manner already described. When this occurs the connection is at once established from the toll line to the distant exchange and this fact is indicated by the lighting of the signalling 55 lamp SL because relay Slr of the switching trunk operates in parallel with Ppr of the preparation circuit at the *e* wire of the outgoing trunk. The toll operator, on receiving 60 this signal, releases the transfer key TK and 65 restores the preparation key PHK so that the

preparation circuit restores to normal as already described.

Referring now to Fig. 3 this shows a toll switching trunk circuit TST which is essentially the same as that illustrated in Fig. 1 70 except that the marking of a group of *d* terminals by the connection of the test relay Ptr is made by a step by step switch under the control of the dial at the toll position instead of by simple direction keys.

In the switching trunk circuit itself the only difference from Fig. 1 is the addition of relay Clr which becomes necessary owing to the fact that the back contacts have to be provided for disconnecting the common stepping relay Isr from the switching trunk circuit. The relay Clr, now having less contacts, can have a make before break contact for locking and a common wire from its resting contact to the front of relay Shr for operating, the multi-contact relay Cgr thus becoming unnecessary.

The direction device in the present circuit comprises the step by step switch S and five relays Zer, Zcr, Rrr, Isr, and Psr, all of 90 which are common to the position. A feature of the step by step switch circuit is that it permits without any change of connections the dialing of one or two digit numbers. If only single digit numbers are used, the 95 switch permits the selection of 10 different directions, but if both 1 and 2 digit numbers are used, then there may be selected up to 19 directions, the numbers corresponding to these directions being 1 to 9 and 01 to 00.

Circuit operation

The operation of the switching trunk circuit itself will not be described in full as it is practically the same as that of the arrangement illustrated in Fig. 1 which has been 105 fully described.

When the toll operator has plugged into the switching trunk jack TJ, the listening key LK and the dialing key DK of the toll cord circuit are thrown. The dial D is directly connected with the common position stepping relay Isr which operates over the back contacts of relay Clr and energizes the slow releasing relay Rrr. A dialing tone or signal is required to indicate the connection of the stepping relay because the stepping circuit, being individual to the position, is always ready for service when the operator begins to set up a toll switching connection. The relay Rrr releases so slowly that it remains operated throughout the dialing of the digits. At the first impulse produced by the dial, relay Isr makes its back contact and over the front of Rrr it energizes Zer and Zcr in series. Zcr is another slow releasing relay which will only release when relay Isr operates for the last time at the end of each series of impulses.

Relay Zer at its right-hand front contact 130

energizes the step by step switch magnet SM, and locks over its left-hand front contact to the interrupter springs I of the switch magnet SM so as to ensure the completion of the 5 step, no matter how short a time relay Isr remains on its back contact. As soon as the magnet SM is fully energized and has opened its interrupter springs I and relay Isr has also energized again, relay Zer falls off opening the circuit for the magnet SM, which makes its first step. This is repeated for each 10 impulse of the digit.

When the last impulse has been sent, relay Isr remains operated, and permits relay Zer 15 to release. Relay Zer provides at its back contact a circuit for relay Psr, via the brush B of the step by step switch. Relay Psr at its right-hand contact closes the circuit for the power magnet I of the finder TF and at 20 its left-hand contact connects the common test relay Ptr over the brush C of the step by step switch to the group of d terminals belonging to the trunks of the direction required.

The trunk finder then continues hunting 25 until a free trunk OJ in the required direction is found, in the manner described in connection with Fig. 1. When this has happened, relays Ptr, Shr, Clr and Cl_r energize and at its back contacts relay Cl_r disconnects relay Isr from the switching trunk circuit and switches the latter through to the selected trunk. The operator receives the signal on lamp SL as previously described 30 and may now proceed immediately to dial out to the distant exchange if that exchange is automatic, otherwise she will restore the dialing key and proceed further with the call in the regular manner.

When relay Cl_r released relay Isr the 40 latter relay opened the circuit of relay Rrr which at its back contact provides a circuit for the step by step switch magnet SM over the arc A and the interrupter springs I of the magnet to restore the switch to its home position. When single digit dialing is used, terminal 10 can be used for a direction on the arc C while on the arc B is will be strapped to terminal 9.

When two digit dialing is to be used, the 45 wiring of the arcs B and C will be as shown on the drawing. If the first digit dialed is 1 to 9 the relapse of relay Zer will operate relay Psr and complete the connection as described above. If the digit is 0, the step by 50 step switch will stop with the brushes on terminal 10 and relay Psr will not become energized, but the circuit will wait for a second digit to be sent in. To this position 55 in the arc B an optional waiting lamp WDL may be wired which lights to remind the operator that a further digit is being waited for. The second digit may be any digit from 1 to 0, thus giving a total of 19 directions. When 60 relay Zer falls off after the second digit, it

will then operate relay Psr and start the finder hunting.

Referring now to Fig. 4 this shows a toll switching trunk circuit TST and preparation circuit PC essentially the same as that 70 shown in Fig. 2 except that the marking of a group of e terminals by the connection of relay Ptr is made by a step by step switch S under the control of the dial at the toll position in the manner described with reference 75 to Fig. 3 instead of by simple direction keys in the switching trunk and preparation circuits. The only other difference consists in the addition of relays Cl_r and Pl_r respectively which become necessary owing to the 80 fact that the back contacts have to be provided for disconnecting the common stepping relay Isr from the switching and preparation circuits. Relays Cl_r and Pl_r now having these contacts can have a make before 85 break contact for locking and a common wire from the resting contact to the front contact of relay Shr for operating, relay Cgr thus becoming unnecessary.

Circuit operation

The operation of this arrangement will not be described in detail since it is thought that the operation will be evident after a consideration of the description of the operation of the arrangements shown in Figs. 2 and 3.

(1) *Toll switching trunk.*—After throwing the junction holding key JHK and thereby energizing relay Jhr, the toll operator throws her listening and dialing keys JIK and DK, thereby closing a circuit for the common stepping relay Isr of the step-by-step switch S over the springs of the dial D. One or two digits are now dialed into the switch S and on the cessation of the impulses 100 a circuit is closed for relay Psr, which completes the circuit for the driving magnet PTF of the finder TF. At the same time the common test relay Ptr is connected to the group of e terminals belonging to the trunks 105 of the direction required. The trunk finder continues hunting until a free trunk OJ is found, and when this happens relays Ptr, Shr, Clr and Cl_r energize, the finder is arrested, the switching trunk is connected to the a and b brushes, and the switch S is restored, 110 all in the manner already fully described with reference to Fig. 3.

(2) *Preparation circuit.*—To set up a connection on the preparation circuit the toll operator depresses the preparation holding key PHK, the dialing key DK and the preparation listening key PLK, and then dials one or two digits characteristic of the wanted 115 direction. The preparation finder PF operates under the control of the switch S to select an idle trunk in the wanted direction in the same manner as the trunk finder TF.

(3) *Transfer of a connection from the* 120

preparation circuit to a toll switching trunk circuit.—This operation is very similar to the same operation which has been described with reference to Fig. 2. As soon as the toll line and switching trunk circuit to which a prepared connection has to be transferred become free, the toll operator throws the junction holding key JHK and the transfer key TK. The transfer key operates relays Dbr, Tpr. Relay Dbr disconnects the *c* brush of all free switching trunk finders so that the finder TF will not test the *c* terminal of any free trunks. Relay Tpr connects the common test relay Ptr to the *e* brush of the preparation finder PF, connects test potential to the *d* brush of the preparation finder PF to mark the selected trunk in the *d* bank of the trunk finder TF, and completes the circuit for the power magnet PTF of the trunk finder TF which was prepared by relay Jhr which operated when the key JHK was thrown. When the *d* brush of the finder TF arrives on the marked terminal this test potential passes over the centering brush *e* of the finder TF, the centering brush *e* of the finder PF, and the inner right-hand front contacts of relay Tpr to the test relay Ptr, which operates and causes the response of relays Shr, Clr and Cl₁r. When this occurs, the connection is at once established from the toll line to the distant exchange, this being indicated by the lighting of lamp SL due to the operation of relay Shr in parallel with relay Ppr over the *c* wire of the engaged trunk. The toll operator on receiving this signal releases the transfer key TK and the key PHK, thereby initiating the restoration to normal of the preparation circuit.

What is claimed is:

1. A circuit arrangement for automatically setting up toll switching connections from an operator's position to distant exchanges in which a toll operator's position is equipped with a plurality of switching trunk circuits each terminating in a finder switch having access to a plurality of groups of outgoing trunks and in which means common to all said switching trunk circuits is provided which, in response to an operation on the part of the operator, sets in operation the finder switch of a switching trunk circuit taken for use by said operator and determines the group of outgoing trunks to be tested by said finder switch, characterized by the provision of a preparation switching circuit including a marking switch for making a connection is adapted to be first made to an idle outgoing trunk to a wanted exchange, and also including means for subsequently transferring said connection, under control of the operator, to a particular switching trunk taken for use.
2. A circuit arrangement for a telephone system, as claimed in claim 1, in which said preparation circuit and said switching trunk

circuits each terminate in a finder switch having access to groups of outgoing trunks extending to said distant exchanges and in which means is provided for causing any one of said finder switches to hunt continuously until it engages an idle outgoing trunk in a group of trunks determined by an operation on the part of said operator.

3. A circuit arrangement for telephone systems as claimed in claim 1, in which said preparation circuit and said switching trunk circuits each terminate in a finder switch having access to groups of outgoing trunks extending to said distant exchanges, and in which means common to said switching trunk circuit is provided for causing any one of said finder switches to hunt continuously until it engages an idle outgoing trunk in a group of trunks determined by an operation on the part of said operator.

4. A circuit arrangement for a telephone system as claimed in claim 1, in which said preparation circuit and said switching trunk circuits each terminate in a finder switch having access to groups of outgoing trunks extending to said distant exchanges, and in which means common to said switching trunk circuits is provided for causing any one of said finder switches to hunt continuously until it engages an idle outgoing trunk in a group of trunks determined by an operation on the part of said operator and in which said common means is adapted to close a test circuit common to a wanted group of outgoing trunks to restrict the finder switch to a hunting movement in that group.

5. A circuit arrangement for a telephone system as claimed in claim 1, in which said preparation circuit and said switching trunk circuits each terminate in a finder switch having access to groups of outgoing trunks extending to said distant exchanges, and in which means common to said switching trunk circuits is provided for causing any one of said finder switches to hunt continuously until it engages an idle outgoing trunk in a group of trunks determined by an operation on the part of said operator and in which said common means is adapted to close a test circuit common to a wanted group of outgoing trunks to restrict the finder switch to a hunting movement in that group, said test circuit extending over terminals of a fourth contact level, all of which are connected together in the same group.

6. A circuit arrangement as claimed in claim 1 in which a testing relay set is provided common to all the finder switches of said operator's position.

7. A circuit arrangement for a telephone system, as claimed in claim 1, in which said preparation circuit and said switching trunk circuits each terminate in a finder switch having access to groups of outgoing trunks extending to said distant exchange and in

which means including a direction key for each group of trunks accessible to the switch and common to the operator's position is provided for causing any one of said finder switches to hunt continuously until it engages an idle outgoing trunk in a group of trunks determined by an operation on the part of said operator.

8. A circuit arrangement for a telephone system, as claimed in claim 1, in which said preparation circuit and said switching trunk circuits each terminate in a finder switch having access to groups of outgoing trunks extending to said distant exchange and in which means including a direction key for each group of trunks accessible to the switch and common to the operator's position is provided for causing any one of said finder switches to hunt continuously until it engages an idle outgoing trunk in a group of trunks determined by an operation on the part of said operator, said direction keys being adapted to close a test circuit common to a wanted group of outgoing trunks to restrict the finder switch to a hunting movement in that group, to close a circuit for the driving magnet of the switch taken for use and to connect a common test relay to the common test circuit.

30 9. A circuit arrangement for a telephone system as claimed in claim 1, in which said preparation circuit and said switching trunk circuits each terminate in a finder switch having access to groups of outgoing trunks extending to said distant exchanges, and in which means comprising a dial and a switch controlled thereby is provided for causing any one of said finder switches to hunt continuously until it engages an idle outgoing trunk in a group of trunks determined by the setting of said dial controlled switch.

10. A circuit arrangement for a telephone system as claimed in claim 1 in which said preparation circuit and said switching trunk circuits each terminate in a finder switch having access to groups of outgoing trunks extending to said distant exchanges and in which means comprising a dial and a switch controlled thereby and common to all the finder switches at said operator's position is provided for causing any one of said finder switches to hunt continuously until it engages an idle outgoing trunk in a group of trunks determined by an operation on the part of said operator.

11. A circuit arrangement for a telephone system as claimed in claim 1, characterized in this that said preparation circuit and said switching trunk circuit each terminate in a finder switch having access to groups of outgoing trunks extending to said distant exchanges, and by means comprising a dial and a switch controlled thereby for starting a selected finder switch and for connecting a test relay common to the operator's position to

the common test circuit of the group of trunks determined by the setting of said dial controlled switch.

12. A circuit arrangement for a telephone system as claimed in claim 1, in which said preparation circuit and said switching trunk circuits each terminates in a finder switch having access to groups of outgoing trunks extending to said distant exchanges and in which means comprising a dial and a single motion switch controlled thereby by a single series of impulses or by the cumulative effect of two or more series of impulses, is provided for causing any one of said finder switches to hunt continuously until it engages an idle outgoing trunk in a group of trunks determined by the setting of said dial controlled switch.

13. In a switching system, an operator's position, a finder switch associated with said position for connecting said position with an idle line in a particular one of a plurality of groups terminating in said switch, means controlled by said operator for causing said switch to establish such a connection, a second finder switch for connecting said position with said lines, and operator controlled means to cause said second switch to take a position determined by the setting of said first switch to transfer said connection from said first to said second switch.

14. In a switching system, an operator's position, a finder switch associated with said position for connecting said position with an idle line in a particular one of a plurality of groups terminating in said switch, means controlled by said operator for causing said switch to establish such a connection, a second finder switch for connecting said position with said lines, and operator controlled means to cause said second switch to take a position determined by the setting of said first switch to establish said connection over said second switch.

15. In a switching system, an operator's position, a finder switch associated with said position for connecting said position with an idle line in a particular one of a plurality of groups terminating in said switch, means controlled by said operator for causing said switch to establish such a connection, a second finder switch for connecting said position with said lines, and operator controlled means to cause said second switch to take a position determined by the setting of said first switch to establish a second connection therefor between said position and said line.

16. In a switching system, an operator's position, a selector switch for connecting said position with a particular one of a plurality of lines terminating in said switch, a second switch, and means for operating it in accordance with the setting of said first switch to transfer the connection between said position and line to said second switch.

17. In a switching system, an operator's position, a plurality of finder switches, a plurality of groups of lines multiplied in the banks of said switches and accessible to said position, means controlled by the operator for determining the particular group of lines to be tested by one of said switches and to cause said switch to hunt in said group for and hold the first idle line of said group, and other means controlled by the operator for causing another of said switches to hunt for said seized line and stop thereon.

In witness whereof, I hereunto subscribe my name this 22nd day of July, 1929.

15
